UNITED STATES PATENT OFFICE.

FRANK S. R. PRENTISS, OF SAN FRANCISCO, CALIFORNIA.

MULTIPLE-PRINTING APPARATUS.

No. 824,813.

Specification of Letters Patent.

Patented July 3, 1906.

Original application filed October 16, 1903, Serial No. 177,241. Divided and this application filed May 11, 1906, Serial No. 259,888.

To all whom it may concern.

Be it known that I, FRANK S. R. PRENTISS, a citizen of the United States, residing in the city and county of San Francisco and State 5 of California, have invented new and useful Improvements in Multiple-Printing Apparatus, of which the following is a specification.

My invention relates to improvements in apparatus for reproducing photographic prints in large quantities and by artificial light. Its object is to provide means for simultaneously printing onto a continuous sensitized strip from a number of plates or negatives, 15 which may vary greatly in density one from another or from a single negative, and so regulating the light that the exposure for all parts of all the plates or the entire surface of a single plate will be uniform.

It consists of the parts and the construction and combination of parts, as hereinafter more fully described and claimed, having reference to the accompanying drawings, in which—

Figure 1 is an elevation, in partial section, 25 of my machine. Fig. 2 is a similar view taken on line X X, Fig. 1. Fig. 3 shows a plurality of negatives secured to a translucent plate. Fig. 4 is a sectional view on the line 30 y y of Fig. 3.

The prints to be developed or toned, according as a "developing-paper" or a "printing-out paper" is used, are in the form of a continuous strip, (represented in the drawings 35 by the character A.) B represents the frame of the printing apparatus.

The sensitized roll of paper or fabric to be printed on is mounted in a dark chamber 4 in frame B upon a roller 5. The end of the roll 40 is carried between the tension-rollers 6 beneath the glass plate 8, carrying the negative or negatives from which the positive impressions are to be printed, and over the stationary platform 7, disposed in a central 45 opening in frame B. For convenience the plate 8 may be considered the negative itself, although it will be understood that several smaller plates, each having a separate image, 50 may be secured to the under side of plate 8, as shown in Fig. 3.

The top of the platform or table 7 is covered with felt or other soft material, and the paper is adapted to be moved intermittently across this surface with its film side up and 55 adjacent to the film side of the superposed

plate, the plate being lifted to allow the paper to travel forward and then being pressed down upon the strip A during the printing period.

The plate 8 is removably clamped in a suitable vertically-reciprocating skeleton carrier 9, which may be operated by a foot-lever 10. By pressing down on the lever the plate is raised from the paper and may be held in elevated position by engaging the stop 11 on 60 the handle 12 under the edge of the top of the frame to allow for the intermittent forward movement of the paper.

Passing over table 7 and under plate 8 the printed paper is received between a second 70 pair of friction-rollers 13 into the storage-chamber 14 of frame B, whence it is drawn continuously through the successively-arranged developing or toning, fixing, and washing baths and over the drier, which mechanisms 75 are not here shown. The paper is moved intermittently beneath the printing-plate 8 by any suitable means—as here shown the hand-crank 15 on one of the rollers 13. The printing of the image upon the sensitized paper A is done by artificial light emanating from a series of incandescent bulbs or lamps 16, carried on vertically and individually adjustable stems 17, disposed above plate 8, the stems 17 being slidable in suitable sockets in a support 18 and being locked at any point by the set-screws 19. These lamps are so arranged that the intensity of light at any point on the plate may be varied to cause all parts of the image-surface to print equally. 80 Frequently when printing in a uniform light it is necessary to give one portion of a negative more time than another. With different negatives these differences in exposure are the more noticeable.

My design is to secure a mean exposure for the entire plate, irrespective of the lights and shadows of the plate. Any number of lamps may be used corresponding with the size of plate 8, which may be several square feet in 90 area.

Having by experiment adjusted the individual lamps, so that all portions of the negative surface will print to the right degree in a certain determinate and equal period of time, 100 the operation of printing may be carried on indefinitely.

The present application is a division of my original application, filed October 16, 1903, Serial No. 177,241.

Having thus described my invention, what I claim, and desire to secure by Letters Patent, is—

1. In a printing apparatus, the combination of a frame having a central opening and compartments at each side of said opening, a stationary support disposed in the opening and over which the paper to be printed on is adapted to travel, means for advancing the paper to be printed on over said support, a translucent plate movable to and from the support, a movable frame supporting said plate, a lever to reciprocate the frame, and means connected with the lever and including a stop engageable with the frame, to hold the plate out of contact with the support.

2. In a printing apparatus, the combination of a frame having a central opening and compartments at each side of said opening, a stationary support disposed in the opening and over which the paper to be printed on is adapted to travel, means for advancing the paper to be printed on over said support, a translucent plate movable to and from the support, a movable frame supporting said

plate, a lever to reciprocate the frame, means connecting with the lever and including a stop engageable with the frame, to hold the plate out of contact with the support, and a series of lamps disposed to illuminate the area of said plate, and means for varying the distance of the individual lamps from said plate to affect locally the printing qualities thereof.

3. In a printing apparatus of the character described, the combination of a paper-supporting surface, a translucent plate, a plurality of separate and smaller plates secured to the first plate and bearing images, a series of lamps, and means for varying the distance of individual lamps from said surface, said translucent plate being interposed between said surface and the lamps.

In testimony whereof I have hereunto set my hand in presence of two subscribing witnesses.

FRANK S. R. PRENTISS.
